RECORDING MECHANISM

Frank V. Mayo, Stockton, Calif.

Application February 14, 1934, Serial No. 711,235

10 Claims. (Cl. 234—63)

This invention relates to a recording mechanism, for sales computing and indicating registers, and particularly to one for use in connection with a liquid dispensing pump of the clock type.

The present application also is a continuation in part of my application on recording and invoicing device for liquid dispensing pumps, Serial No. 537,846, filed May 16, 1931.

10 When incorporated in a liquid dispensing pump the device will enable a visual record of the actual quantity of liquid dispensed to be presented to any customer, so that he may not only be sure that he has obtained full measure, but will have a permanent record of the transaction.

The principal object of my invention is to provide a device of this character adapted to use a long strip of recording paper printed in the form of blank tickets spaced lengthwise along the strip, 20 and constructed so that with a single turning operation of a hand shaft through a predetermined arc (preferably one full revolution) the ticket will be stamped at the proper place, the stamping device returned to its initial inactive 25 position, and the strip advanced the length of a ticket. This last movement advances the stamped ticket so that it is accessible to the operator for tearing from the remainder of the strip for presentation to the customer.

30 At the same time, a duplicate ticket is automatically stamped and retained in the machine for the records of the owner or operator.

A further object of the invention is to produce a simple and inexpensive device and yet one which 35 will be exceedingly effective for the purpose for which it is designed.

These objects I accomplish by means of such structure and relative arrangement of parts as will fully appear by a perusal of the following 40 specification.

In the drawings similar characters of reference indicate corresponding parts in the several views:

Figure 1 is a sectional elevation of my improved recording mechanism, showing the position of the 45 parts in their normal position or prior to a strip impressing and advancing operation.

Figure 2 is a similar view showing the position of the parts just as the punch or impressing device is being operated.

50 Figure 3 is a plan view of a blank invoice ticket, detached from the strip.

Referring now more particularly to the characters of reference on the drawings, the device comprises a housing fragmentarily illustrated at 55 1 in which is mounted a platform 2 having a con-

tinuous circular slot or groove 3 therein. A supply of paper 4 is supported in the casing below the platform, the supply being made in the form of at least two superimposed strips, an outer one 5 and an under one 6. Both strips are printed in the form of longitudinally extending blank invoice tickets 7 as shown in Fig. 3, the outer strip being preferably roulette or otherwise weakened for easy tearing between adjacent tickets as indicated at 8. The under surface of the strip 5 is carboned so that an impression of any writing thereon will be transferred to the under strip. From the supply, the strips pass between upper and lower feed rolls 9 and 10 respectively, disposed adjacent one end of the platform. The strips then pass over the platform, the upper one 5 projecting through a slot 11 in the casing parallel to and adjacent the level of the platform, and the under strip 6 also passing through said slot and then reentering the casing through a lower slot 12 and being then wound on a removable take up spool 13 mounted in the same manner as a camera take up spool. By reason of this arrangement, an outer ticket may be written on when projected through the casing and the writing will be impressed on the corresponding ticket of the under strip.

The lower feed roll 10 carries a pinion 14 positioned to engage a mutilated gear 15 fixed on a hand shaft 16, the ratio of the gear and pinion relative to the size of the feed roll and the length of the ticket being such that with each full revolution of the hand shaft, the strips will be advanced along the platform exactly the length of one ticket. A slip-belt drive 17 connects the roll 10 and the take-up spool. The ratio of the belt drive relative to the speed of the feed roll is such that when the spool is empty, a full revolution of the hand shaft is just sufficient to wind the same length of paper thereon as is advanced by 40 the feed roll. As the spool rolls up, a lesser amount of rotation of the same is of course necessary to wind said length of paper thereon. The belt then slips and merely holds the paper snugly wrapped about the spool.

Projecting upwardly from above the platform concentric with the slot 3 is a vertical shaft 18. This is adapted to be rotated through a full turn or less with the operation of the apparatus in which the recording mechanism is installed by a gear connection 19 with a driven shaft 20. Each ticket has a circular dial 21 printed thereon and marked to indicate different quantities (such as gallons). This dial is substantially the same diameter as slot 3 and is disposed on the ticket so 55

that when the latter is on the platform at the end of a strip advancing operation, the dial is centered with the slot.

Slidably but non-turnably mounted on the 5 lower end of shaft 18 is a sleeve 22 having a radial arm 23 projecting from its lower end. A punch 24 depends from this arm in line with slot 3, but normally above the platform and paper. Above the arm the sleeve has a flange 25 engaged by the bifurcated end of the adjacent leg 26 of a bell crank unit which is turnably pivoted above the platform on a cross shaft 27. The other leg 26a of the bell crank depends on one side of the platform and rides on a cam 28 secured on shaft 16.

The cam 28 is arranged so that the bell crank will be maintained idle and the sleeve held lifted except at a certain point R on the cam which is raised sufficient to cause the bell crank arm 26a 20 to be lifted and the sleeve to be depressed so that the punch will perforate the ticket resting on the platform, as indicated at P in Fig. 3. The raise R occupies a predetermined position relative to the mutilated portion of the gear 15 as will be 25 seen.

The end of each printed ticket, to the sides of the dial thereon, is provided with a pair of holes 29 which, when the dial on the invoice is concentric with the punch shaft 18, registers 30 with openings 30 in the platform. Vertical fingers 31 aligned with the openings 30 are mounted above the platform as a unit with a vertically movable guided frame 32. The bottom of this frame is normally engaged and held raised by 35 one end of a pivoted lever 33 which in turn is engaged and normally prevented from dropping by the upturned end of the arm 34 pivoted in a fixed position at one end above the shaft 16. This arm is formed with a depending latch element 35. This normally rides on the circular 40 portion of another cam 36 on the shaft 16, the lever 33 and the finger 31 being then held raised. The cam however is formed with a notch N adapted to receive the latch element 35, at which 45 time the arm, lever and finger are lowered to cause the fingers to project through the openings 29 and 30, and thus positively hold the paper in a centered position and against movement ready to be punched.

50 This notch N is arranged so that the finger dropping operation takes place at the completion of a punching, paper feed, and punch resetting cycle. Also the latch element engaging in the notch enables the operator to tell, by the 55 feel, that such cycle of operations is completed and the structure ready for another liquid dispensing operation. The notch is also positioned just ahead of the punch controlling cam raise R, so that upon the subsequent rotation of the 60 handle from its latched position the punching operation is performed almost immediately.

To reset the punch, another gear 37 is mounted to mesh with the mutilated gear and which gear 37, for convenience of assembly, is mounted on the shaft 27 but has no connection with the punch operating bell crank. A slip drive 38 connects this gear with the shaft 20 of the machine.

Prior to operating the pump or other structure to dispense liquid the parts of the recording or control mechanism are as shown in Fig. 1. In other words, the paper holding fingers 31 are lowered, (passing through holes 29 in the adjacent ticket) the punch sleeve 22 is raised and 75 the gear 37 and pinion 14 are both clear of the

teeth of the gear 15. When the shaft 20 is then rotated with the operation of the machine, the punch arm is rotated about the invoice dial to a position corresponding to the amount of liquid dispensed. While the gear 37 will then be 5 rotated due to its driving connection with the rotating shaft 20, no rotation will be imparted to the gear 15 since the teeth of said gears are not then in engagement.

When the dispensing operation is halted the 10 operator writes whatever is necessary on the portion of the ticket about to be punched and which already projects somewhat from the casing and rotates the shaft 16 in the direction indicated by the arrow. This causes the cam raise R to 15 drop the bell crank arm 26 and cause the punch to be depressed as shown in Fig. 2, perforating the ticket dial as indicated at P in Fig. 3. With a slight further rotation of the crank handle the punch is raised and at the same time the 20 fingers 31 are also raised clear of the ticket by the movement of the cam 36 relative to the latch element 35, causing the latter to be moved out of the notch N. The teeth of the gear 15 then engage the teeth of the gear 37 and 25 impart rotation in the resetting direction to the shaft 20 and thence punch shaft 18.

Shortly after the gear 15 engages the gear 37, it also engages the pinion 14, feeding the paper along the platform to dispose a fresh ticket 30 under the punch and causing the ticket just punched to be projected from the casing of the apparatus in position to be grasped and torn off by the operator. Just before the hand shaft 16 has completed a full revolution the teeth of 35 the gear 15 leave the pinion 14. A further feeding of the paper is thus halted so that when the holding fingers 31 are dropped by the engagement of the latch 35 in the notch N at the completion of the revolution of the hand shaft, 40 the paper is stationary and will not be torn by the descending fingers. At this time also the teeth of the gear 15 are clear of the gear 37 so that the latter is free from connection with the recording mechanism and can rotate, with a 45 subsequent dispensing operation as previously explained, without moving said mechanism.

From the foregoing description it will be readily seen that I have produced such a device as substantially fulfills the objects of the invention as set forth herein. 50

While this specification sets forth in detail the present and preferred construction of the device, still in practice such deviations from such detail may be resorted to as do not form a departure from the spirit of the invention, as defined by the appended claims. 55

Having thus described my invention, what I claim as new and useful and desire to secure by Letters Patent is:

1. A recording apparatus including with a rotatable shaft, a platform on which to support a recording strip disposed beyond and at right angles to the shaft, a strip impressing device extending radially of the shaft in overhanging relation to the platform, means normally holding the device clear of the platform, a rotatable operating shaft, means actuated by the initial rotation of the operating shaft to depress the device to a strip impressing position and then retract the same, and means actuated by the further rotation of the operating shaft to advance the strip. 65

2. A recording apparatus including with a rotatable manually controlled shaft, a recording-strip supporting member, an impressing device 70

- movable over the member from a predetermined starting position, and mechanisms controlled by a continuous rotation of said shaft from a predetermined starting position, to first cause the device, after movement thereof from said starting position, to impress the strip, then return the device to said starting position, and then advance the strip.
3. A recording apparatus comprising with a driven shaft, a strip of paper movable under the driven shaft, a normally raised strip impressing device mounted for rotation with the shaft and movable downwardly on the shaft from such raised position to a strip impressing position, a rotatable hand shaft, and mechanisms controlled by a continuous rotation of said hand shaft from a predetermined position and through an arc of predetermined extent to first lower the device to a strip impressing position, then raise the device clear of the strip, and then advance the strip.
4. A recording apparatus including with a rotatable manually controlled shaft, a recording-strip supporting member, an impressing device movable over the member from a predetermined starting position, and mechanisms controlled by a continuous rotation of said shaft from a predetermined starting position, to first cause the device, after movement thereof from said starting position, to impress the strip, then return the device to said starting position, and then advance the strip, and means controlled by and functioning with the operation of the shaft to hold the strip against movement at the termination of the advancing movement thereof and until the completion of a subsequent strip impressing operation.
5. A recording device including with a rotatable manually controlled shaft, a recording-strip supporting member, an impressing device movable over the member from a predetermined starting position, and mechanisms controlled by a continuous rotation of said shaft from a predetermined starting position, to first cause the device, after movement thereof from said starting position, to impress the strip, then return the device to said starting position, and then advance the strip, a depressible paper holding finger mounted above and normally clear of the strip, and means between the finger and the shaft to cause said finger to be depressed into engagement with the strip at the completion of the strip advancing operation and to be again raised clear of the strip at the completion of a subsequent strip impressing operation.
6. A recording apparatus including with a rotatable manually controlled shaft, a recording-strip supporting member, an impressing device movable over the member from a predetermined starting position, and mechanisms controlled by a continuous rotation of said shaft from a predetermined starting position, to first cause the device, after movement thereof from said starting position, to impress the strip, then return the device to said starting position, and then advance the strip, a depressible paper holding finger mounted above the strip supporting member, a cam on said rotatable shaft, and means between said cam and finger to hold the latter raised from the strip while the latter is being advanced and allowing said finger to drop after the advancing operation is completed.
7. A recording apparatus comprising with a shaft driven in one direction, from an initial
- position, a strip of paper movable under the driven shaft, a radial arm mounted for rotation with the shaft and depressible thereon from a predetermined raised position, said arm carrying a strip impressing element normally clear of the strip, a hand shaft, and instrumentalities operatively connected to and functioning with the continuous rotation of the hand shaft through a single revolution only from a predetermined starting point for first depressing the arm to impress the strip, then raising said arm, then rotating the driven shaft in a retractive direction to its initial position, and then advancing the strip a predetermined amount.
8. A recording apparatus including with a shaft driven in one direction from a predetermined starting position, a strip of paper movable under the driven shaft, a radial arm mounted for rotation with and downward movement on said shaft from a normal raised position and carrying a strip impressing element normally clear of the strip, a hand shaft, a cam on said shaft, means between the cam and arm to depress the latter only when said hand shaft is in a predetermined position, and to raise the arm when the hand shaft is in a further position, a feed spool engaging the strip, a pinion fixed with the spool, a mutilated gear fixed on the hand shaft to engage the pinion; the teeth of the mutilated gear being arranged to clear the teeth of the pinion before the cam is in position to actuate the arm depressing means and to remain clear of the pinion teeth until the arm has been depressed and again raised, and means between the hand shaft and the driven shaft to return the latter to its starting position after the arm has been raised.
9. A recording apparatus comprising a platform, a recording strip mounted to pass over the platform, a take-up spool about which said strip is wound beyond the platform, means above the platform to mark the strip at predetermined spaced points in its length, and means to selectively advance the strip a distance between adjacent points and at the same time wind the strip on the take-up spool; said last named means comprising feed rolls between which the strip passes ahead of the platform, means to positively drive one of said rolls, and slip-drive means between said one roll and the take-up spool.
10. A recording apparatus including with a rotatable manually controlled shaft, a recording-strip supporting member, an impressing device movable over the member from a predetermined starting position, and mechanisms controlled by a continuous rotation of said shaft from a predetermined starting position, to first cause the device, after movement thereof from said starting position, to impress the strip, then return the device to said starting position, and then advance the strip, a depressible paper holding finger mounted above the strip supporting member, a cam on said rotatable shaft, a pivoted arm having an element intermediate its ends riding on the cam, said arm having an upturned free end, and another pivoted arm overhanging and resting on said upturned end of the first named arm and supporting the finger, the cam being shaped so that the last named arm may drop and allow the finger to engage the strip only for a relatively short arcuate portion of the peripheral extent of the cam and after the strip advancing operation is completed.

FRANK V. MAYO.
